HIGH-VOLTAGE WINDING

John F. Calvert, Irwin, Pa., assignor to Westinghouse Electric & Manufacturing Company, East Pittsburgh, Pa., a corporation of Pennsylvania

Application November 13, 1935, Serial No. 49,519

16 Claims. (Cl. 171—206)

My invention relates to windings for dynamo-electric machines, and it has particular relation to high-voltage windings for polyphase machines.

In the United States, the larger polyphase generators have been built for potentials of 16,500 to 24,000 volts, which have been found to be the most economical voltage from the standpoint of the insulation and construction of the generator. Generators wound for voltages appreciably higher than the present standard are larger in diameter, longer in length, and more costly than units wound for the most economical voltage. However, the difficulties associated with switching equipment, cables, and station structures, in handling alternating currents of large magnitudes at the generating stations, emphasize the need for large-capacity generators wound for higher voltages of from 27,600 to 33,000 volts, or even higher.

Long experience with generators insulated with mica insulation in the slots has thoroughly demonstrated that there is an ample factor of safety on the slot insulation. Means have also been developed for bracing and insulating the end-turns or end-connections so that the insulation at these points will also safely withstand the potential stresses imposed upon it.

In high-voltage machines, however, there is a more serious difficulty in connection with corona, which must be kept small at the normal operating voltage because of the resulting generation of nitrous oxide, in an air-cooled machine, which is particularly disadvantageous in machines having a closed-circuit system of ventilation, which is a preferred form of ventilation for these machines. In such machines the nitrous oxide is retained in the enclosure, in the presence of an excessive amount of moisture, gradually increasing in concentration, and forming weak acids which attack the fins of the air-cooler and which deteriorate the organic insulation on the end-winding connections, phase-connecting rings or group-connectors, and bracing members.

Not only must the corona be kept small at the normal operating voltage, but it is very desirable also to avoid it at the prescribed test voltage of twice normal voltage plus 1000 volts, particularly in machines designed for very high voltages, because corona becomes particularly vicious in its nature at extremely high voltages, developing a tendency to bunch badly and to concentrate at one point, so that considerable damage can be done, at least to the outward appearance of the insulation, if corona is present during the minute for which the test voltage is applied.

Means have heretofore been developed for preventing the occurrence of corona on the straight parts of the coil-sides, where the coil-insulation comes into contact with the iron of the stator slots. At one time, this was the principal source of corona; but it has been effectively eliminated by the application of a coating of semi-conducting material over the insulation of the coil-sides, as set forth in two Patents Nos. 1,784,989 and 1,784,990, issued to C. F. Hill on December 16, 1930.

If this external coating of semi-conducting material were extended over the end-connections, corona problems could be eliminated there also, as well as on the straight coil-sides, but it would then become necessary to make the end-turn insulation as effective as that on the straight coil-sides. This is difficult to accomplish, because the contour of the end-turns is such that it is hard to apply the insulation so that it is free of air-voids. It has become customary, therefore, not to attempt to make the insulating wrappings or coverings over the end-turns or end-connections as reliable, in dielectric strength, as the insulation of the coil-sides lying within the slots, and hence it has been necessary to utilize insulating materials for the separating blocks or spacers and for the clamping members which are utilized to hold the end-connections in place.

It has been found to be possible to eliminate corona on the end-turns, at the normal voltages which have heretofore been common, by properly spacing the end-connections and by grading off the high-resistance slot-insulation coating and properly distributing the voltage stresses on the portions of the end-turns which are closest to the slots, by means such as are described and claimed in my Patent No. 2,061,502, November 17, 1936.

At higher voltage ratings, however, and particularly at the prescribed test-voltage of twice normal plus 1000 volts, difficulties have been experienced with end-turn corona on normal machines which have been supplied with ordinary two-layer windings. In a two-layer winding utilizing pre-formed coils, one coil-side of each coil is placed in the bottom of its proper slot, and this process is completed at least part way around the machine, before the second coil-side of any coil is placed in its proper slot, so that one coil-side of each coil lies in the bottom of its slot, and the other coil-side lies in the top of its slot, or in a cylindrical layer which is at a different radial depth than the first coil-side. This type of winding has become the accepted type which

is utilized whenever possible, because of its facility of manufacture, during the process of laying the coils in the slots, and because of the compactness of its end-connections. It involves difficulties, however, as a result of corona, in machines of higher-than-standard voltages, and particularly at the test-voltages which must be applied thereto before the machines can be put into actual use.

10 A so-called single-layer winding has also been known, in which all of the coil-sides are at the same radial depth in the various slots, all lying in a single cylindrical layer. This type of winding has been resorted to, when necessary in order 15 to reduce the number of coil-sides so as to reduce the voltage of the winding, but it has had the disadvantage of an increased manufacturing cost for labor in assembling the coils, and somewhat more bulky end-connections in the finished 20 machine, and greater pole-face losses and other iron losses, particularly with chordings which are materially different from full-pitch coils.

According to my invention, I utilize a double-deck single-layer winding, or two (or more) 25 single-layer windings laid one above the other, and suitably connected in series, so that the coil-sides may occupy precisely the same places (except for their order of connection in series) which they would occupy in an ordinary two- 30 layer winding, so that the pole-face losses and other iron losses will be no greater than in a machine having an ordinary two-layer winding. My double-deck single-layer winding, however, 35 produces a machine in which the end-connections of the coils are disposed in four different so-called "conical" layers, rather than two, so that much greater spacings can be obtained between adjacent coil-portions of different voltages, than would be practically possible in a two-layer winding, as will be more fully described hereinafter.

A further important object of my invention is to obtain the benefits of the principle of graded insulation, in a machine utilizing pre-formed coils, or on coils having the same amount of insulation on each of its two coil-sides. The general principles of graded insulation are well known, and call for the grading of the insulation, or the application of an amount of insulation which is commensurate with the maximum voltage appearing on any given portion of the conductor, this grading being done in two or more steps. Attempts to apply the principle of graded insulation to the windings for dynamo-electric machines have heretofore resulted in 50 rather costly structures, such as a construction involving the use of straight bars for the coil-sides, and separately formed pieces for the end-connectors, requiring four joints per coil.

By reason of my utilization of a plurality of 60 single-layer windings it becomes a very simple matter to make the different layers of different insulation-strengths, and to connect the layer having the lowest insulation-strength closest to the neutral point of the generator, thus obtaining the benefits of a graded insulation in a winding utilizing pre-formed coils. In this manner, that is, by the use of graded insulation in an economical winding which does not require separate bars and end-connectors, I can obtain considerable savings in space required for insulation, and hence in the size and cost of the machine, or I can obtain a much higher voltage-rating for a given size of machine, thus compensating, at least in part, for the increased difficulty of winding, and the increased space occupied by the end- 75

connections, which are characteristic of the single-layer winding. The resulting design makes it possible for me to produce a machine of higher-than-usual voltage, with only a relatively slight increase in cost, as compared to a machine of a voltage such as has heretofore been standard in the United States.

In making the over-potential tests on a machine having windings of graded insulation, it is necessary, of course, for each of the windings 10 of the two (or more) different insulations to be tested separately at a potential corresponding to its class of insulation, that is, twice its normal voltage plus 1000 volts. This involves some slight difficulties, which are in effect no 15 more serious than the necessity for bringing out separate terminal-leads for the two windings, at least temporarily for the period of the test.

The utilization of the principle of graded insulation on high-voltage polyphase generators 20 also involves greater hazards as a result of excessive voltages such as are produced by lightning or switching operations, particularly lightning. It is an important feature of my present invention that I overcome these hazards by providing means, at the neutral point of the generator, for providing a ground connection which is effective at least during excess-voltage discharges, and by providing lightning arresters connected from ground to the several junction 25 points between windings of different insulation-strengths, at one or more intermediate points of the winding, and in each of the phases. This is a new principle in lightning-arrester protection which constitutes, I believe, a valuable part 30 of my solution to the problem of successfully building a generator of higher-than-usual voltage at a minimum cost. The cost of the additional protective equipment is relatively insignificant as compared to the reduction in generator-cost which is brought about by the utilization 35 of graded insulation.

With the foregoing and other objects in view, my invention consists in the constructions, combinations, connections, systems and methods hereinafter described and claimed and illustrated in the accompanying drawings, wherein 40

Figure 1 is a wiring diagram of one embodiment of my double-deck single-layer winding, with the protective equipment which is utilized for protecting the same against lightning,

Fig. 2 is a somewhat diagrammatic fragmentary longitudinal sectional view of a portion of the end of a dynamo-electric machine embodying my invention, showing the bracing 50 of the end-connections,

Fig. 3 is a transverse sectional view through the coil-sides lying in one of the stator slots,

Fig. 4 is a diagrammatic view illustrating the circumferential spacing between adjacent end- 60 connections of my single-layer winding,

Fig. 5 is a similar view applying to a double-layer winding, and

Fig. 6 is a view similar to Fig. 1, showing another embodiment.

Figs. 1 to 4 illustrate a double-deck single-layer winding such as is described and illustrated in a paper by C. M. Laffoon and myself in Electrical Engineering for June, 1935, vol. 54, pages 624-631. The winding is designed for a three-phase, Y-connected, high-voltage, 4-pole generator, comprising a rotor-member 50, a portion of which is indicated in Fig. 2, and a stator-member 51 comprising a magnetizable slotted core 52 carrying my novel winding, a 75

development of which is shown in Fig. 1. The winding, as shown, consists of two superimposed single-layer windings 53 and 54, of different insulation-strengths, although more than two layers 5 may be utilized, as will be obvious. The coil-sides of these windings, or the portions which lie in the slots 55 of the stator-core 52 (Fig. 3), may be disposed in any order, with the high-insulation winding 54 in either the top or 10 the bottom of the slot: as shown, it is in the top of the slot.

In Fig. 1, the low-voltage winding 53 is indicated diagrammatically with dotted lines, and the various low-voltage coil-sides occupying the 15 slots of the stator are indicated by relatively short straight dotted lines 56. The high-voltage winding 54 is illustrated in full lines, and its coil-sides are indicated by relatively long straight full lines 57. The low-voltage and 20 high-voltage windings 53 and 54 are made up of pre-formed coils each consisting of two coil-sides 56 and 57, respectively, lying in the slots of the machine, and end-connections 58 at each 25 end of the machine.

25 The particular machine shown is a four-pole machine having forty-eight slots which are numbered consecutively from 1 to 48 in Fig. 1. Each slot carries a low-voltage coil-side 56 and a high-voltage coil-side 57. For convenience in 30 forming the coils, the coils are shown as being substantially full-pitch coils, having a span of the full-pitch, or 12 slots, plus or minus one slot, which is necessary for the purpose of working out the winding. It is quite feasible, 35 however, to utilize charded windings rather than substantially full-pitch windings.

In Fig. 1, as is common in winding-diagrams, each coil is illustrated as if it consisted of a single turn. As is usual, however, particularly 40 in a high-voltage machine where the maximum number of turns must be connected in series in order to obtain the high voltage, each coil actually consists of a plurality of turns, and Fig. 1 may be regarded as illustrating, therefore, only 45 the terminal connections of the coils, after the conductor has finished going around, between the two slots in which its coil-sides are disposed, as many times as is necessary in order to complete the requisite number of turns per coil.

50 In Fig. 3 it is seen that each coil consists of three turns, made up of a conductor 59 which is first lightly insulated, as indicated at 61, to provide the small amount of insulation which is necessary between turns, the three conductors 55 being subsequently bound together into a single coil, by means of heavier insulation 62, so that each coil is adequately insulated from ground, (assuming the stator-core 52 to be grounded), according to the voltage of the winding of 60 which the coil forms a part. For convenience in fabrication, each conductor 59 is sub-divided into a plurality of strands of flat, uninsulated, copper straps, all lying together and treated as if a single solid conductor had been utilized.

65 In addition to the coils comprising the coil-sides 56 and 57, respectively, and the end-connections 58, previously described, each of the single-layer windings 53 and 54 also comprises a plurality of phase-connecting rings or group-connectors 63 and 64, respectively.

All of the end-connections, including the end-turns 58 of the coils and the connecting rings 63 and 64, are braced or supported, and insulated from each other, by means of suitable 75 insulating pieces 65 (Fig. 2) mounted on metal-

lic supports 66 which are bolted to the end of the stator-core 52. The end-turns 58 are disposed in a plurality of so-called "conical" layers as indicated in Fig. 2 by the numerals 67, 68, 69, and 70, the word "conical" being utilized 5 in its generic sense which includes the limiting case of a plane circle, which is the case in which the end-turns 58 are bent down at right-angles with respect to the coil-sides 56 and 57, as shown in Fig. 2. It will be understood, of course, that this angle of bending the end-turns 10 may be less than a right-angle.

In Fig. 1, one complete phase of my double-deck single-layer winding is indicated in heavy lines, for convenience in tracing out the winding. 15 Starting at terminal-conductor T1, it will be seen that the heavy-line phase of the winding consists first of two high-voltage coils 72 and 73, respectively, constituting one pole of that phase of the high-voltage winding 54, the beginnings and 20 ends of these coils being numbered in Fig. 1. The coil 72 has coil-sides lying in slots 7 and 29, and the coil 73 has coil-sides lying in slots 9 and 22. From the coil 73, the circuit continues, through a group-connector 74, to coils 75 and 76, 25 constituting a second pole of that phase of the high-voltage winding 54, from which the circuit continues, through a group-connector 77, to two coils 78 and 79 constituting a third pole of that 30 phase of the high-voltage winding, from which the circuit continues, through a group-connector 81, to two coils 82 and 83 constituting the fourth pole of that phase of the high-voltage winding, after which the circuit is completed, by the end-connector 84, to the junction point J1 between the 35 high- and low-voltage windings of the phase T1.

From the junction point J1, the winding circuit is continued through the corresponding phase of the low-voltage winding 53, starting out 40 through the coils 86 and 87 constituting the first pole of this phase of the low-voltage winding, and continuing on, through all four poles, to the neutral terminal T4, which is the star point of the Y-connected windings. By a comparison of the low-voltage coils 86 and 87 with the high-voltage 45 coils 72 and 73 of the same pole, it will be observed that the low-voltage coils are displaced two slot-pitches to the left of the high-voltage coils, so that it is evident that the low-voltage winding is 2/12 of 180°, or 30° out of phase with the high-voltage 50 winding, thus giving the same effect as a charded winding.

Attention has already been called to the fact that the end-turns or end-connections 58 of the coils are disposed in four different axially displaced layers which are indicated in Fig. 2 by the numerals 67 to 70. In each layer of the end-connections the conductors are all inclined the same way around the circumference of the core member; that is, they do not cross each other. The 55 cross-overs from one layer to another are provided by bends 89 and 90 as indicated in Figs. 1 and 2. In each single-layer winding, in the form shown in Figs. 1 and 2, the end-connections lying in any given layer 67 to 70 of the end-connections 60 consist of conductors emanating from (or leading to) every other slot, so that the circumferential spacing between these end-connections, in any given layer of the end-connections, corresponds to 65 two slot-pitches of the stator core. 70

Reference to Fig. 4 will show this spacing of the end-connections more clearly. This figure shows an end view of a few coils of the low-voltage winding 53. The end-portions 92, 93, and 94 lie in the conical end-connection layer 67; and the end 75

portions 95, 96, 97, and 98 lie in the conical end-connection layer 68. It will be seen that the adjacent end-portions, as 92, 93, in any layer, come from alternate slots 55 of the stator-core 52.

5 The significance of the spacing depicted in Fig. 4, for my single-layer winding, will be better appreciated by comparison with Fig. 5, which is a corresponding view of a double-layer winding, in which there are only two conical layers of end-connections at each end of the machine, for the entire winding of the machine. The end-portions 101, 102, and 103 are in one layer, and the end-portions 104, 105, and 106 are in the other layer. It will be noted that the adjacent end-portions, as 101 and 102, in any one layer, come from adjacent slots 55.

20 A comparison of Figs. 4 and 5 will show that the center-to-center spacing 107 between adjacent end-connections in any conical layer of the single-layer winding (Fig. 4) is approximately twice the corresponding spacing 108 for the double-layer winding; while the air-spacing 109 between the adjacent single-layer end-connections of the single-layer winding (Fig. 4) is approximately three times the air-spacing 110 between the adjacent end-connections in a double-layer winding (Fig. 5). The significance in these greater spacings, in the single-layer winding, as a means for avoiding corona, will readily be understood.

30 It will be noted that the single-layer winding by which I have illustrated the principles of my invention in Figs. 1 to 4 include end-portions, in any conical layer of end-connections, separated circumferentially by a uniform spacing of two slot-pitches of the core-member, which gives, to be sure, a wide spacing 107 and 109 (Fig. 4) between the end-portions of coils of different phases, which is what is desired, but it also gives the same spacing between the end-portions of coils of the same phase, which is not really necessary, because the largest voltages appear between coils of different phases rather than between adjacent coils of the same phase. I desire that the embodiment of my invention shown in Fig. 4 shall be taken, therefore, as an illustration of the principle of securing a wide spacing between conductors of different phases, in any conical layer of the end-connections, regardless of the details of how the winding is worked out, to bring about this result.

45 Fig. 6 illustrates the principles just described, by showing a double-deck single-layer winding in which the adjacent end-portions 112 and 113 of coils of the same phase, in any conical layer of the end-connections, are spaced by a single slot-pitch, whereas the adjacent end-portions 113 and 114 of coils of different phases have a spacing of three slot-pitches, thereby affording even greater protection against corona than the winding shown in Figs. 1 to 4.

50 Fig. 6 also illustrates a different embodiment of my invention in that the individual coils, such as the coil 112-115, are charded to $\frac{5}{6}$ pitch, and the high- and low-voltage windings have their corresponding phases connected together so that the corresponding portions of the two windings are 30° out of phase with each other, thereby giving substantially the same effect as the winding shown in Fig. 1, but with end-connections which are considerably shorter because of the $\frac{5}{6}$ chording.

55 The problem of building a high-voltage generator-winding is not solved unless the winding-insulation can be made so that it will withstand

the surges which will surely be present on any line to which the generator is connected. These surges, particularly those resulting from lightning discharges, which cause the severest surges, produce two effects on the winding-insulation. In the first place, there is the question of the voltage-stress of the insulation 61 (Fig. 3) between adjacent turns of a coil, particularly in the coils near the line-ends, during a surge-discharge; and in the second place, there is the question of a possible breakdown of the insulation between each coil and ground or the frame of the machine.

60 It has heretofore been demonstrated that the problem of extremely unequal distribution of the surge-voltage between successive coils of the winding, thus tending to produce turn-to-turn breakdown between the over-stressed turns, can be prevented from being a serious problem if no waves of steep wave-front are permitted to reach the winding; and hence I utilize a wave-sloper 20 such as is described and illustrated in connection with Fig. 14 of a paper by Fielder and Beck in A. I. E. E. Transactions for October, 1930, vol. 49, pages 1582-1583. This wave-sloper, as shown in Figs. 1 and 6, comprises, for each line-wire L₁, L₂ and L₃, first a lightning arrester 116, connected from line to ground, for limiting the magnitude, or the maximum crest-voltage, of the incoming lightning-surge; next an inductance coil 117, connected in series with the line between this lightning arrester and the machine; and finally a capacitor 118, connected between the machine-terminal of the inductance coil 117 and ground, for sloping off the incoming surge and causing it to take a longer time to reach its crest-value. It is preferable also to utilize a second lightning arrester 119 in parallel to the capacitor 118, for limiting the possible maximum value of the sloped-off lightning wave. By this means, already known in the art, it is possible to avoid serious problems resulting from unequal distribution of the surge-voltage between the successive turns of the winding, thus protecting the turn-to-turn insulation.

65 The problem of protecting the ground-insulation, between each of the coils and ground, against the over-voltages of lightning-surges, is a more serious problem for which I have devised a solution in the form of intermediately connected lightning arresters 121, 122, and 123 for protecting the ground-insulation of the low-insulation part of a graded-insulation winding, as described and illustrated in my article in Electrical Engineering for January, 1934, vol. 53, pages 139-146. These lightning arresters 121, 122, and 123 are 50 connected respectively between the junction points J₁, J₂ and J₃ and ground. They not only limit the maximum possible crest-value of the lightning-surge which may reach the low-voltage winding 53, but they also serve materially to improve the distribution of the surge-voltage between the several turns of the various individual coils and also between the several coils of the winding. Thus, if each of the coils of the low-voltage winding took just a small percentage more than its proportionate share of the incoming lightning-surge voltage, the voltage-stresses between successive turns of any coil will not be excessive, but the cumulative potential-difference between the last low-voltage coil and ground 60 might well be much more than the low-voltage ground-insulation would stand, in a graded-insulation winding such as mine.

65 I have found that the intermediately connected arresters 121, 122, and 123, when utilized in con- 75

nection with a suitable neutral-point grounding-means, such as an impedance device 124 in Fig. 1, or a lightning arrester 125 in Fig. 6, serve to so correct the distribution of the lightning-voltage among the coils of the generator-winding as to prevent these excessive coil-to-ground stresses.

I have not made any effort to illustrate or to describe the corona-preventing coatings which will be utilized both on the straight coil-sides and on portions of the end-connections, as these coatings, while they will preferably be utilized, and probably must be utilized, do not comprise any part of my present contribution to the art.

By a proper application of the principles of my present invention it becomes economically feasible to very materially increase the rated voltages of large alternating-current generators, and to provide a generator-winding which will withstand the test voltage of twice normal plus 1000 volts without any evidences of corona, and which will withstand any surges which may be impressed thereon from lightning-disturbances on the line to which the generator is connected.

I claim as my invention:

1. An alternating-current electric machine having a slotted core-member, and an alternating-current winding having coil-sides lying in the slots of said core member, said winding comprising a plurality of superposed layers of single-layer windings having a plurality of diverse insulation-strengths.

2. A polyphase electric machine having a slotted core-member, and a polyphase, star-connected winding having coil-sides lying in the slots of said core-member, said winding comprising a plurality of superposed layers of single-layer windings, at least one of said single-layer windings having a lower insulation-strength than another of said single-layer windings and being serially connected therewith, with the low-insulation winding connected nearer to the star point of the polyphase winding.

3. A polyphase electric machine having a slotted core-member, and a polyphase, star-connected winding having coil-sides lying in the slots of said core-member, said winding comprising a plurality of superposed layers of single-layer windings, each of said single-layer windings comprising formed coils of continuous conductors, at least one of said single-layer windings having a lower insulation-strength than another of said single-layer windings and being serially connected therewith, with the low-insulation winding connected nearer to the star point of the polyphase winding.

4. A polyphase electric machine having a slotted core-member, and a polyphase, star-connected winding comprising a plurality of superposed single-layer windings; each single-layer winding comprising all of the coil-sides lying in any given cylindrical layer in the slots of the core-member, and two layers of end-connections at each end of the core-member; each layer of end-connections being comprised of coil-portions all inclining the same way around the circumference of the core-member; the closest coil-portions of different phases, in each layer of end-connections, being separated circumferentially by a plurality of slot-pitches of the core-member.

5. A polyphase electric machine having a slotted core-member, and a polyphase, star-connected winding comprising a plurality of superposed single-layer windings; each single-layer winding comprising all of the coil-sides lying in any given cylindrical layer in the slots of the

core-member, and two layers of end-connections at each end of the core-member; each layer of end-connections being comprised of coil-portions all inclining the same way around the circumference of the core-member; the closest coil-portions of different phases, in each layer of end-connections, being separated circumferentially by a plurality of slot-pitches of the core member; at least one of said single-layer windings having a lower insulation-strength than another of said single-layer windings and being serially connected therewith, with the low-insulation winding connected nearer to the star point of the polyphase winding.

6. A polyphase electric machine having a slotted core-member, and a polyphase, star-connected winding comprising a plurality of superposed single-layer windings; each single-layer winding comprising all of the coil-sides lying in any given cylindrical layer in the slots of the core-member, and two layers of end-connections at each end of the core-member; each layer of end-connections being comprised of coil-portions all inclining the same way around the circumference of the core-member, successive coil-portions being separated circumferentially by two slot-pitches of the core member.

7. A polyphase electric machine having a slotted core-member, and a polyphase, star-connected winding comprising a plurality of superposed single-layer windings; each single-layer winding comprising all of the coil-sides lying in any given cylindrical layer in the slots of the core-member, and two layers of end-connections at each end of the core-member; each layer of end-connections being comprised of coil-portions all inclining the same way around the circumference of the core-member, successive coil-portions being separated circumferentially by two slot-pitches of the core-member; at least one of said single-layer windings having a lower insulation-strength than another of said single-layer windings and being serially connected therewith, with the low-insulation winding connected nearer to the star point of the polyphase winding.

8. A polyphase electric machine having a slotted core-member, and a polyphase, star-connected winding comprising a plurality of superposed single-layer windings; each single-layer winding comprising all of the coil-sides lying in any given cylindrical layer in the slots of the core-member, and two layers of end-connections at each end of the core-member; each layer of end-connections being comprised of coil-portions all inclining the same way around the circumference of the core-member; the coils per phase per pole, in each of the single-layer windings, being disposed in adjacent slots; and the end-portions of adjacent coils of different phases, in any layer of end-connections, being separated by more than two slot-pitches.

9. A polyphase electric machine having a slotted core-member, and a polyphase, star-connected winding comprising a plurality of superposed single-layer windings; each single-layer winding comprising all of the coil-sides lying in any given cylindrical layer in the slots of the core-member, and two layers of end-connections at each end of the core-member; each layer of end-connections being comprised of coil-portions all inclining the same way around the circumference of the core-member; the coils per phase per pole, in each of the single-layer windings, being disposed in adjacent slots; the end-portions of adjacent coils of different phases, in any layer of

end-connections, being separated by more than two slot-pitches; at least one of said single-layer windings having a lower insulation-strength than another of said single-layer windings and being 5 serially connected therewith, with the low-insulation winding connected nearer to the star point of the polyphase winding.

10. A polyphase electric machine having a slotted core-member, and a polyphase, star-connected winding having coil-sides lying in the slots of said core-member, said winding comprising a plurality of serially connected polyphase windings of different insulation-strengths, the lowest-insulation winding being star-connected, and the 10 phases of another winding being serially connected to the phases of the lowest-insulation winding, means for providing a ground-connection at the star point for excess-voltage discharges, and a separate voltage-limiting lightning 15 arrester connected between ground and each phase-terminal junction-point between two windings of different insulation-strengths at some intermediate point in the machine-winding.

11. A polyphase electric machine having a slotted core-member, and a polyphase, star-connected winding comprising a plurality of superposed single-layer windings, each single-layer winding comprising coils having a pitch which is 25 within one slot of being full-pitch, at least one of said single-layer windings having a lower insulation-strength than another of said single-layer windings and being serially connected therewith, with the low-insulation winding connected nearer to the star point of the polyphase winding.

12. A polyphase electric machine having a slotted core-member, and a polyphase, star-connected winding comprising a plurality of superposed single-layer windings having coil-sides lying in the slots of said core-member, one of said 30 single-layer windings being star-connected, and the phases of the other single-layer windings being serially connected to the corresponding phases of said star-connected winding, with a slight phase-difference between at least two of 35 said single-layer windings.

13. A polyphase electric machine having a slotted core-member, and a polyphase, star-con-

nected winding comprising a plurality of superposed single-layer windings having coil-sides lying in the slots of said core-member, one of said single-layer windings being of different insulation-strength than another of said single-layer windings, the lowest-insulation single-layer winding being star-connected, and the phases of another single-layer winding being serially connected to the phases of the lowest-insulation winding, with a slight phase-difference between at 10 least two of said single-layer windings. 5

14. A polyphase electric machine having a slotted core-member, and a polyphase, star-connected winding comprising a plurality of superposed single-layer windings; each single-layer 15 winding comprising charded coils of less than full pitch; and series-circuit connections embracing first all of the coils corresponding approximately to a particular phase in one layer, and then all of the coils corresponding approx- 20 imately to said phase in another layer.

15. A polyphase electric machine having a slotted core-member, and a polyphase, star-connected winding comprising a plurality of superposed single-layer windings; each single-layer 25 winding comprising charded coils of less than full pitch; at least one of said single-layer windings having a lower insulation-strength than another of said single-layer windings and being serially connected therewith, with the low-insulation 30 winding connected nearer to the star point of the polyphase winding.

16. A polyphase electric machine having a slotted core-member, and a polyphase, star-connected winding comprising a plurality of superposed single-layer windings; each single-layer winding comprising charded coils of less than full pitch; at least one of said single-layer windings having a lower insulation-strength than another of said single-layer windings and being 35 serially connected therewith, with the low-insulation winding connected nearer to the star point of the polyphase winding, and with a slight phase-difference between the serially connected 40 single-layer windings.
